UNITED STATES PATENT OFFICE

EDWARD E. KLEINSCHMIDT, OF CHICAGO, ILLINOIS, ASSIGNOR TO TELETYPE CORPORATION, OF CHICAGO, ILLINOIS, A CORPORATION OF DELAWARE

SELECTIVE SYSTEM AND APPARATUS THEREFOR

Application filed November 11, 1925. Serial No. 68,307.

The present invention relates to improvements in selective systems and apparatus therefor.

More particularly the invention relates to an improvement in methods of operating printing telegraph systems and in printing telegraph shift control mechanisms.

In printing telegraph machines for transmitting the stock market quotations letters are ordinarily printed in one line while the figures are printed in another line. As a result, when the usual form of permutation code printers is used for this class of transmission many more shift operations occur than in ordinary message transmission. After each group of letters or figures a special shift or unshift combination must be transmitted and the speed of transmission is slowed up materially. For this reason permutation codes have not heretofore displaced the step by step stock ticker systems. In emergency signalling, as for example in fire alarm and police telegraph systems where the usual type of printing telegraph machines with the ordinary shift controls are utilized the operator may fail to send the shift and unshift signals properly, with the result that at critical times the matter transmitted becomes unintelligible.

In accordance with the present invention the number of shift operations is reduced by adding to the character selecting impulses of each signal a shift selecting impulse which will operate only to determine whether a letter or a figure is to be printed. In Baudot or permutation code printers, a sixth selecting impulse is added to the five character selecting impulses of each signal transmitted. Mechanical and electrical means are provided to carry out the invention and in the preferred embodiments are so arranged that the printer shift mechanism will remain in either figures or letters position as long as figures or letters are transmitted successively, and will change the position only when the transmis-

sion changes from figures to letters or from letters to figures.

Accordingly, an object of the present invention is to provide a novel method of signalling in which the special shift and unshift signals ordinarily transmitted in permutation code systems are eliminated and in which a shift or unshift signal is transmitted as part of each character combination.

A further object of the invention is the provision of novel shift mechanisms for permutation code printing telegraph machines especially adapted for the rapid printing of matter such as stock quotations in which a great many shift operations occur, without the transmission of special shift and unshift signals.

Still further objects of the invention will appear hereinafter in the detailed disclosure of preferred embodiments of the invention and are such as may be attained by utilizing the various combinations and subcombinations hereinafter set forth and as defined by the terms of the appended claims.

Referring to the drawings, Figure 1 is a fragmentary sectional elevation showing one form of shift mechanism involving the principles of the invention.

Figure 2 is a fragmentary end elevation of the form shown in Figure 1.

Figure 3 is a detailed fragmentary view showing the shift control selector bar mechanism.

Figure 4 illustrates a section of a stock ticker tape.

Figure 5 is a fragmentary side elevation partially in section showing the essential parts of a modification of the invention.

Figure 6 is a fragmentary side elevation partially in section of a further modification of the invention.

Figure 7 is a fragmental side elevation partially in diagram showing the invention as applied to a multiple magnet printer.

Figures 8 and 9 illustrate a preferred em-

bodiment of the invention in which the mechanism is shifted only when required to effect the printing of characters in the proper case.

5 As shown in Figures 1 to 3 inclusive, the subject matter of the present case is a continuation in part of the subject matter in copending application Serial No. 656,857, filed August 11, 1923, now Patent 1,567,599, 10 granted Dec. 29, 1925, and only so much of the mechanism shown in the copending application has been here disclosed as will be necessary for a complete understanding of the present invention. Accordingly reference 15 characters applied to like parts in the present case are the same as the characters applied to the same parts in the copending case, and the copending application may be readily referred to for a full understanding of the various details of the selector and printing mechanisms not herein fully set forth. The selector bars 59 to 63 and the shift control bar 501 shown in Figure 1, may be controlled mechanically by a single selector magnet as 25 set forth in the copending case, or may be controlled by selector magnets individual thereto from a rotary distributor in either a multiplex or a start stop signal printing telegraph system in any manner well known to 30 the art. The type bar action comprising the actuating bars 108, arms 113, type bars 116 and the action of the printing bail parts 125 to 129, the action of the spacing mechanism controlled by the parts 166 to 169, and the 35 ribbon feeding actuating mechanisms, and the various other printing actions will be fully understood by a reference to the copending case.

The mechanism related to the present invention comprises platen block 488 mounted on a head 489 which is mounted slidably in a guide bracket secured to frame 400. An extension 491 of member 489 is pivotally linked to a rocker arm 492 which is pivotally supported from frame 400 at 493. Ribbon shift pivot 318 is secured to and movable with an extension 494 of arm 492. A spring 595 connected to arm 492 tends to throw arm 492 with 488 and 489 forward into shifted position. 50 Block 488 is just wide enough to be positioned under one of the characters carried by type bars 116 as shown in Figure 1. Secured to head 489 are a plurality of members 495, which, as the head is moved in the shift operation are arranged to depress the edges of the tape in order to insure contact with the tape of only the one character under which block 488 has been interposed. It will be seen that according to the position of arm 55 492 either an upper or lower case character will be printed, and the ribbon will be properly shifted by the movement of extension 494.

A pin 496, secured to 492, is in slidable engagement with a slot in the end of a shift operating member 497. Member 497 is pivoted

at a point 498 and urged to the right in Figure 1 by a spring 499, to maintain a cam projection 500 thereon, against bar 125 of the printer bail operating frame. A special shift control bar 501 is added to notched selector bars 59 to 63, and an extra cam, selector finger and latch, are added to the selector cam shaft shown in the copending application to control this bar by a line impulse in the same manner as the selector bars 59 to 63 are controlled. The signal periods, when this bar is added in a start stop printing system will be made up of eight intervals, namely, a start interval, five selector bar control intervals, a shift control interval, and a stop interval. The transmitter will be arranged to transmit a marking condition in the shift control interval when block 488 is to be shifted to print an upper case figure, and to transmit a spacing condition when block 488 is to remain in the letter printing position. The selector cams will of course be spaced accordingly, in proper angular and axial position.

A stop projection 502 is carried by bar 501 in such a position that it will be directly beneath the end of shift control bar 497 when bar 501 is in unactuated position, and a wide slot is cut directly beneath bar 497 in all the notched selector bars so that bar 497 can move into these wide slots with the selector bars either in actuated or unactuated position. When a marking impulse is received during the shift control interval, bar 501 will be permitted to move to the left in Figure 3 under the influence of its spring 65, and as the printing bail moves upward, bar 497 will rock on its pivot 498 under the influence of spring 499 with cam projection 500 in engagement with bar 125, and will move into the wide selector bar slots. The actuating bar 108 selected by the arrangement of the notched bars will also be moved into its aligned slots. When the two bars have reached the bottoms of their respective slots, bar 497 will have moved to a position which will have caused arm 492 to be moved by spring 595 to shift block 488 into its forward or upper case position. The printing stroke of the selected type bar will then commence and there will be no further movement of bar 497 until the printing has been effected and the selected type bar has returned to normal. Then the return or downward movement of the printer bail frame will cam the selected actuating bar 108 and bar 497 out of the aligned slots. As soon as the bars 108 and 497 have been lifted clear of the notched selector bars, member 77 is actuated by cam 90 to restore the selector bars and the shift control bar 501 to unactuated position, when stop projection 501 will again be positioned under bar 497. Until another code combination, with a marking impulse in the seventh intervals is received, bar 501 will be locked in the position shown in Figure 3 by its control

finger, and platen block 488 will be held to the rear or in lower case position as shown in Figure 1.

In Figure 5 a modified form of the invention is disclosed in which the platen and platen carriage construction shown in Figure 3 of the copending application is modified. The platen construction and the carriage are the same as shown in the copending application and the tape together with the platen is shifted bodily. A shift control member 503 suitably pivoted on a point 504 to the frame (not shown) has the upper end thereof normally held against the projection 502 of the shift control bar 501. An actuating projection 506 formed on member 503 is urged into engagement with the printer operating bail member 125 by the spring 505. Pivoted to the lower end of the member 503 by means of pin 507 is a shift control latch member 508. Member 508 is provided with extension 509 normally held in engagement with an edge of the member 503 by means of helical spring 510 which may be coiled around 25 and supported on an extension of the pin 507 (not shown). A carriage shift bell crank member 511 is pivotally supported from the frame by means of a pin 512 and is normally urged counter clockwise by the spring 513, 30 until a projection 514 thereof engages the end of the latch member 508. Pivoted secured to the end of one arm of the bell crank member 511 by means of pin 515 is a link 516. Link 516 is provided with a guide slot 517 35 adjacent the upper end thereof through which the guide pin 518 extends. Guide pin 518 is suitably secured in the supporting framework and guides and limits member 516 in a reciprocating motion. The upper end of member 40 516 is adapted to be engaged by the lower surface of the printer actuating bail member 128. Formed on the other arm of the bell crank member 511 are the extensions 519 between which a pin 520 is positioned. Pin 520 45 is secured to the member 420 of the platen carriage. Secured to the member 420 are the ribbon shifting elements 319 and 324 which shift the ribbon in position for printing when the carriage is shifted as will more fully appear by a reference to the copending application. As set forth in the copending application projection 415 of the member 420 is adapted to engage the stop screws 442 and 443 and will limit the travel of the carriage. 50 Supported from the member 420 is a carriage positioning roller or member 521 which is adapted to ride over the projection 522 of the limiting member 523. Member 523 is pivotally mounted and urged preferably by a 55 spring (not shown) into yielding engagement with the roller or member 521.

In operation of this form of the invention the parts are normally positioned as shown and the platen together with the tape 60 (not shown) will be positioned to receive

printing impressions of the selected type bars in lower case or unshifted position. As the printing bail structure moves to effect printing strokes in a manner more fully set forth in the copending application, the stop 514 will engage the end of latch member 508 and motion of the bell crank member 511 under influence of spring 513 will be prevented. When, however, a character in the upper case is selected the shift control bar 501 will be actuated and will shift the projection 502 from beneath the end of the member 503. As the printing bail moves in its printing stroke, spring 505 will shift member 503 clockwise about its pivot 504 under control of the printing bail member 125, and the cam projection 506 and the end of latch 508 will be shifted to the left in Figure 5 until it is disengaged from the stop member 514. As soon as this disengagement occurs spring 513 will shift the bell crank member counterclockwise and the right extension thereof will engage the pin 520 and will shift the member 420 together with the platen and tape into the upper case or shifted position. The parts are so proportioned and arranged that the movement of the platen into shifted position will be completed before a printing impact of the selected type bar is effected. After the printing of the selected character has been effected the printing bail structure will be returned, as more fully set forth in the copending case, and the selected type bar will return to unactuated position. As the printing bail structure returns to normal and moves the member 128 downward the side of member 128 will engage the end of link 516 and will force the bell crank 511 in a clockwise direction. At the same time bar 125 will move the member 503 until the end of latch 508 drops behind the projection 514 and projection 502 of the bar 501 is moved to the position shown in Figure 5. During the return movement of the printing bail structure, member 125 will engage the cam projection 506 of member 503 and will force the end of the member 503 out of the aligned selector bar slots. During this motion of the member 503 the end of the latch 508 will engage the left side or edge of the projection 514 and the latch 508 will move about pin 507 as a pivot until the return movement of the printer bail permits spring 510 to force the latch 508 into position shown in Figure 5. When this occurs the parts will be locked with the platen and tape in unshifted or lower case position.

In the form shown in Figure 6, a further modification of the invention is shown in which the carriage is moved to the upper case or shifted position by means of a cam member and is restored by means of a spring. In this form the shift actuating bar of the copending application together with the cam extension 433 thereof and the carriage actuating rollers 431 and 436 are retained as set forth in

the copending application. The carriage together with the platen and tape as shown in Figure 3 of the copending application is normally held by means of a spring 524 secured thereto and to an extension 525 of a spring post with the roller 436 carried by the member 420 in engagement with the cam extension 433. When a selected character is to be printed in the lower case position the projection 502 of the bar 501 prevents motion of the shift actuating bar 108 into the aligned slots and the platen will remain in the position shown in Figure 6, as printing of the selected character is effected. When, however, the character is to be printed in the upper case or shifted position, in addition to selection of the type bar carrying the character to be printed the bar 501 is selected and the shift control bar 108 will move into the aligned slots as the printing bail moves in its printing stroke. As the bail moves in its printing stroke cam member 433 will be shifted vertically and will force the carriage together with the platen and tape into position to receive the upper case or shifted character impression just before the printing impact of the selected tape bar. As the parts restore to normal spring 435 will move the shift actuating bar downward and spring 524 will effect the return of the platen carriage to normal or unshifted position as shown in Figure 6.

In the forms of the invention so far described the shift mechanism automatically restores to normal position after each shift movement, and must be moved from normal position each time a character is to be printed in the shifted position. This introduces unnecessary movement in the mechanism when successive characters in the shifted position are to be transmitted. In the preferred embodiments of the invention herein-after set forth, the shift mechanism will remain in a given case position until a different position is required for the printing of a succeeding character.

In the form of invention shown in Figure 7 the shift arrangement shown in Figure 1 is modified for application to a multiple magnet printer, and is so arranged that the shift mechanism is actuated only when the case position is to be changed for the printing of the character but the shift selecting condition is transmitted with each character as above set forth. This is accomplished by eliminating the actuating lever 497 for the platen shift arm 492, and eliminating the shift pulse control selector bar 501. The platen arrangement is the same as shown and described in connection with Figure 1, and only the changed parts will be here described. Arm 492 is actuated by a link 526 connected thereto at one end against the tension of spring 527. The other end of the link 526 is pivotally connected to a plunger 528 of the solenoid 529. One terminal of solenoid

529 is connected by means of the conductor 530 to shift control contact 1 of the multiplex distributor 531. Distributor brush 532 successively connects the segments 1 to 6 of each channel of the multiplex system through ring 531 to the line, in well known manner. Segments 2 to 6 are connected to selector magnets (not shown) which control the positioning of selector bars 59 to 63 in well known manner and as more fully set forth in the copending application. The other terminal of solenoid 529 is connected by conductor 534 to a terminal of the winding of locking relay 535, the other terminal of which is connected at 536 to the conductor 530 and to armature 537 of relay 535. Armature 537 is adapted to connect the conductor 530 and winding 535 to the positive pole of an electrical source of supply when relay 535 is energized. Conductor 534 is connected through normally closed contacts 539 and 540 to the negative pole of the electrical supply. Contacts 539 and 540 are controlled by the member 541 carried on an end of the lever 542 pivotally supported at 543 from the printer frame. The end 544 of lever 542 is positioned in a manner to be engaged at the end of a printing stroke by the printing bail 128. An inductive shunt resistance 546 is preferably connected across conductors 530 and 534 to make the relay 535 slow to release so that contacts 537 and 538 will remain closed until brush 532 returns to segment 1.

In operation of this form of the invention the code combinations of selecting impulses in each channel are received in the usual manner, and distributed to the proper segments 2 to 6 of the distributor causing the setting of the selector bars 59 to 63 in selective combinations. To each code combination of impulses, a shift control interval is added so that each signal is made up of the usual permutations of selecting conditions and an added shift control condition. When a lower case character is to be printed, the shift control pulse or condition is a spacing condition and printing will occur with the platen in the position shown in Figure 7. If an upper case character is to be printed, a marking condition is set in the shift control interval of the signal and positive potential will be placed on contact 1 of the distributor by brush 532. Relay 535 and solenoid 529 will then energize over the circuits from contact 1, conductors 530 and 534, and contacts 539 and 540 to the negative pole of the supply source. Energization of solenoid 529 positions platen 488 to receive a printing impact from the upper case letter of the type bar selected by the code combination of impulses, and energization of relay 535 completes a locking circuit through contact 538 and tongue 537 for solenoid 529 insuring the holding of platen 488 in upper case position until after the printing impact of the selected character.

After the printing impact is completed bail 128 will engage end 544 of lever 542 causing movement of member 541 to separate contacts 539 and 540 interrupting the locking circuit 5 through solenoid 529 and relay 535.

If the inductive resistance 546 is omitted, the platen will then return to lower case position under influence of spring 527, until another upper case character is to be printed.

10 However, in the preferred embodiment of the invention the resistance 546 will be utilized, and in this case relay contacts 537 and 538 will be held closed until the brush 532 returns to segment 1 in the next cycle. If the 15 next character to be printed is in the shifted position relay 535 will again be energized from the distributor contact 1 and the platen will be held in shifted position. It will be noted that the action of the printer mechanism 20 is such that the locking circuit through contacts 539 and 540 is broken near the end of the cycle so that a comparatively small prolongation of the energization of relay 535 will provide sufficient overlap to hold the mechanism 25 in shifted position while a number of characters are printed in succession in the same case position and until a character is to be printed in lower case or unshifted position of parts.

30 While the shift control pulse has been disclosed as the first pulse of the signal combinations and this arrangement is preferable because a maximum time is allowed for the shift operation before the printing impact, 35 it will be understood that any other impulse of the signal combination may be utilized to control the shift mechanism. It will also be understood that arrangements shown in Figures 5 and 6 may be modified in like manner 40 for magnet operation of the shift mechanisms. The magnet shift control may also be applied to operate the shift mechanism of any of the well known permutation code printers which may thereby be adapted for 45 use in a system embodying the present invention.

In the form of invention shown in Figures 5 and 9, a preferred embodiment is disclosed in which the shift mechanism is mechanically actuated, and the platen remains in one 50 position until a character is to be printed in a different case position. In this form of the invention the platen 488 and the platen block 489 are supported on and slidable on the member 490 as set forth in connection with Figure 1, and the tape feeding and supporting means in this form of the invention are the same as are shown in Figure 1 to which a 55 reference may be had for a full understanding of the parts. Platen block 489 is formed integrally with or rigidly secured to the actuating extension 547 to which the ribbon shifting parts are connected at 318. The rear end of the actuating extension 547 is pivotally 60 connected by means of pin 549 to one end of

supporting link or member 550 which at its other end is pivoted at 551 to the frame 400 of the printer. Rotatably supported on the pin 549 at opposite sides of the extension 547 are shift and unshift rollers 552. The shift roller 552 in the Figure 8 engages an edge of the cam extension 553 of shift actuating bar 554. The opposite edge of the cam extension 553 reacts against a roller 555 which is pivotally supported on an extension of the frame 400. Suitably supported from the frame 400 is an unshift reacting roller or member 556, against which one edge of the unshift cam extension 557 of the unshift actuating bar 558 is held by means of spring 559. Shift and unshift actuating bars 554 and 558 are provided with cam projections 110 and actuating shoulders 111 such as are provided on actuating bars 108. Shoulders 111 are adapted to be engaged by the printing bail 128, and cam projections 110 held in engagement with the bar 125 of the printing bail structure by means of the springs 560.

Shift control selector bar 501 is provided with a projection 561 which in the unactuated or unselected position of the bar 501 prevents movement of shift actuating bar 554 to the right in Figure 8 into the aligned slots 562 of the selector bars 59 to 63 and the actuated or selected position of bar 501 permits movement of actuating bar 554 into the aligned slots 562 during a printing stroke of the bail structure. Bar 501 is also provided with a projection 563 which in the selected or actuated position of the bar 501 is positioned beneath the unshift bar 558 and prevents movement thereof into the aligned slots 564 of the bars 59 to 63 during a printing stroke of the bail structure and in the unactuated or unselected position of the bar 501 the unshift bar 558 is permitted to move into the aligned slots 564 of the bars 59 to 63. In order to insure the proper positioning of the platen 488 in the shifted or unshifted position a bell crank member 565 suitably supported from the frame 400 on a pivot 566 is provided with a triangular projection 567 which is forced into engagement with one of the rollers 552 by means of a spring 568. Projection 567 is so proportioned with relation to the roller 552 that the platen will be yieldingly held in either case position by the action of spring 568, which is of sufficient strength to hold the parts properly in either case position but permits shifting of the parts under the influence 115 of the cam members 553 and 557.

In operation of this form of invention when a character is to be printed in the unshifted or normal position, the selection is set up on the selector bars 59 to 63 as above set forth and shift control selector bar 501 will remain in unactuated position with the projection 561 positioned beneath the shift actuating bar 554. After the selection has been set up on the selector bars, the printing mech- 130

anism is tripped and the bail structure moves upward in a printing stroke, permitting the selected actuating bar 108 and the unshift bar 558 to move into the aligned slots. As 5 the movement of the printing bail structure continues the bar 128 will engage the shoulder 111 of the selected actuating bar 108 and the unshift bar 558, causing a printing stroke of the selected type bar and an upward movement 10 of the cam extension 557. If the platen is in unshifted position, the upward movement of the bar 558 will have no effect. However, if the parts are in shifted position, the upward movement of the cam extension 557 15 will move between the roller 556 and the unshift roller 552 and will force the extension 547 and the platen block 489 to the right in Figure 8, before a printing impact of the selected character occurs. So long as the 20 characters received are to be printed in the unshifted position, the platen 489 will remain in the position shown. As soon as a character is to be printed in the shifted position of the parts, bar 501 will be selected and will move 25 to the position shown in Figure 9. In this position of the parts, extension 561 will be moved out of alignment with shift actuating bar 554, and projection 563 will be positioned in alignment with unshift actuating bar 558. 30 As the printing bail structure moves in a printing stroke unshift actuating bar 554 and the selected actuating bar 108 will move into the aligned slots in the selector bars 59 to 63, and will then be moved across the 35 aligned slots by the bail 128. This effects a printing stroke of the selected type bar and an upward movement of the cam extension 553 which forces the extension 547 forward positioning the platen 488 in shifted position. 40 Platen 488 will remain in shifted position until the selector bar 501 is positioned in unselected or unactuated position for the printing of the character to prevent actuation of bar 554 and causing actuation of the unshift 45 bar 558. The parts will then be restored to the position shown in Figure 8 and will remain until another character is to be printed in the shifted position of the platen.

Accordingly, having described preferred 50 embodiments of the invention, what is desired to be secured by Letters Patent and is claimed as new is:

1. A printing telegraph receiver comprising a selecting mechanism embodying a plurality of notched permutation members responsive to code combinations of uniform marking conditions and uniform spacing conditions; printing means embodying a plurality of groups of characters, each group being 55 selectable by a different code combination; a shift mechanism for determining the character of a selected group to be printed and means responsive to a special shift selecting condition added to said code combinations 60 controlling said shift mechanism.

2. A printing mechanism comprising a plurality of type bars each carrying a plurality of characters; a plurality of actuating bars controlling said type bars; a paper feed mechanism coacting with said type bars; a platen movable independently of said paper feed mechanism to determine the character on a selected type bar to be printed; and a selecting mechanism responsive to signal combinations each made up of a shift control interval and permutation of type bar selecting intervals simultaneously controlling said type bars and said platen. 70

3. In a printing telegraph machine; a printing mechanism comprising a plurality of groups of characters; a shift mechanism normally held in position to cause printing of the characters in one of said groups by means of a spring; means for moving said shift mechanism against the tension of said spring to print characters in another of said groups; and permutation selecting means responsive to received code combinations of selecting conditions controlling said printing mechanism, and responsive to a selecting condition added to each code combination controlling said first mentioned means. 80

4. In a combination a printing mechanism; a notched permutation selecting mechanism controlling said printing mechanism; a plurality of distributor contacts controlling said selecting mechanism; a shift mechanism; an operating magnet for said shift mechanism; and a distributor contact controlling said magnet independently of said selecting mechanism. 90

5. A printing telegraph receiver comprising a plurality of character elements each of said elements being provided with a shift and unshift character, a printing mechanism arranged to co-act with either of said characters on said character elements, means responsive to a uniform code combination of received impulses for selecting one of said character elements and means responsive to an added impulse for operating said printing mechanism to co-act with either the shift or unshift character. 100

6. A printing telegraph receiver comprising a plurality of character elements a shift mechanism and permutation means on said receiver responsive to code combinations of impulses for simultaneously selecting one of said character elements and operating said shift mechanism. 110

7. In a printing telegraph receiver a plurality of character elements, a plurality of permutation members responsive to code combinations of impulses for selectively operating one of said character elements, an additional member arranged to respond to an impulse accompanying said code combinations of impulses, a shift mechanism and a member operated by said additional member for moving said shift mechanism. 120

8. In a printing telegraph receiver, a plurality of character elements, a plurality of permutation members responsive to code combinations of impulse conditions for selecting said character elements, a shift control member selectively operated by a single impulse condition accompanying said code combination of impulse conditions, and a shift bar controlled by said shift control member for operating the shift character selected.

9. In a printing telegraph receiver, a plurality of type bars, a platen arranged to coact with said type bars and provided with shift and unshift position, means responsive to code combinations of received impulse conditions for selecting one of said type bars for operation and means responsive to an extra impulse accompanying said code combination for positioning said platen to shift and unshift position.

10. In a printing telegraph receiver, a plurality of type bars, a platen arranged to coact with said type bars and provided with shift and unshift position, means responsive to code combinations of received impulses for selecting one of said type bars for operation and means responsive to an extra impulse for moving said platen transversely to shift or unshift position.

11. In a printing telegraph receiver, a platen, a shift bar for controlling said platen, said shift bar being responsive to a single impulse condition accompanying each code combination of selecting impulse conditions to shift said platen.

12. In a printing telegraph receiver a platen having a shift and unshift position, a pivoted shift lever responsive to a single impulse following a code combination of impulses to rotate about said pivot and a connecting member between said shift lever and said platen responsive to the angular movement of said shift lever for moving said platen from either shift or unshift position to its alternate position.

13. In a printing telegraph receiver, a plurality of type bars, a platen having a shift and unshift position, a pivoted shift lever, means responsive to a code combination of impulse conditions for selecting one of said type bars for operation, means responsive to an extra impulse condition accompanying said code combination for turning said shift lever about its pivot and a mechanical connection between said shift lever and said platen whereby the movement of said shift lever moves said platen to its alternate position.

14. In a printing telegraph receiver, a plurality of type bars, a platen having a shift and unshift position, a pivoted shift lever, means responsive to a code combination of impulses for selecting one of said type bars for operation, means responsive to an extra

impulse for turning said shift lever about its pivot and a pivoted connection between said shift lever and said platen whereby the movement of said shift lever operates to move said platen to its alternate position.

15. In a printing telegraph receiver, a plurality of type bars, a platen having a shift and unshift position, a pivoted shift lever, means responsive to a code combination of impulse conditions for selecting one of said type bars for operation, means responsive to a predetermined impulse other than said code combination for turning said shift lever about its pivot, a pivoted connection between said shift lever and said platen whereby the movement of said shift lever moves said platen to its alternate position, and a spring connection to said pivoted connection for urging said platen normally to its unshift position.

16. A printing telegraph receiver comprising a selecting mechanism embodying a plurality of permutation members responsive to code combinations of uniform marking condition and uniform spacing conditions, printing means embodying a plurality of groups of characters, each group being selectable by a different code combination, a shift mechanism for determining the character of a selective group to be printed, and electro-magnetic means responsive to a special shift selecting condition added to said code combination controlling said shift mechanism.

17. In a printing telegraph receiver, a printing mechanism comprising a plurality of groups of characters, a shift mechanism normally held by means of a spring in position to cause printing of the characters in one of said groups, means for moving said shift mechanism against the tension of said springs to print characters in another of said groups, selecting mechanism responsive to a received code combination of selecting conditions controlling said printing mechanism and responsive to a selecting condition added to each code combination controlling said first mentioned means, said selecting mechanism comprising a plurality of notched selector bars responsive to said code combinations and an operating magnet for said shift mechanism controlled independently of said notched selector bars.

18. In combination, a printing mechanism having a normal and shift position, permutation means on said printing mechanism responsive to code combinations of impulses for controlling the operation of said printing mechanism and electro-magnetic means for controlling the shift or normal position of said printing mechanism.

19. In combination, a printing mechanism, permutation selecting mechanism on said printing mechanism, controlling said printing mechanism, a plurality of distributor contacts controlling said selecting mechanism,

- a shift mechanism, an operating magnet for said shift mechanism, a distributor contact controlling said operating magnet independently of said selecting mechanism, and means 5 including a locking circuit for said magnet controlled by said printing mechanism.
20. In combination, a printing mechanism having a shift and a normal position, permutation means on said printing mechanism responsive to received code combinations of impulses for controlling said printing mechanism and means responsive to an impulse preceding said code combination of impulses for controlling said printing mechanism to shift 10 or normal position.
21. In combination, a printing mechanism having a normal and a shift position, notched permutation means on said printing mechanism responsive to received code combinations 15 of impulses for controlling the operation of said printing mechanism and electro-magnetic means responsive to an impulse received by said code combination for controlling the printer to its shift or normal position.
22. In combination, a printing mechanism, notched permutation mechanism in said printing mechanism controlling said printing mechanism, said printing mechanism having a shift and a normal position, electro-magnetic 25 means for controlling the printing mechanism to its shift or normal position, and means for maintaining said electro-magnetic means locked in its operating position.
23. In combination, a printing mechanism having a normal and a shift position, permutation means responsive to code combinations 30 of impulses for controlling said printing mechanism, electro-magnetic means responsive to an impulse preceding said code combination of impulses for controlling said printing mechanism to its shift and normal position, and means for maintaining said electro-magnetic means in a fixed position 35 during succeeding code combinations of impulses while no change in the shift position is taking place.
24. In combination, a printing mechanism, a selecting mechanism controlling said printing mechanism, a shift mechanism, electro-magnetic means for controlling said shift mechanism and means responsive to the operation of said printing mechanism for controlling said electro-magnetic means. 40
25. In combination, a printing mechanism, a selecting mechanism controlling the printing mechanism, a shift mechanism, electro-magnetic means for operating said shift mechanism, said electro-magnetic means being jointly responsive to received impulses 45 and said printing mechanism.
26. In combination, a printing mechanism, means responsive to received code combinations of impulses for operating said printing mechanism, a shift mechanism for said printing mechanism, electro-magnetic means re- 50

sponsive to a received impulse for operating said shift mechanism, said electro-magnetic means being responsive to the operation of said printing mechanism for restoring said shift mechanism to normal.

27. In combination, a printing mechanism, means responsive to received code combinations of impulses for operating said printing mechanism, a shift mechanism for said printing mechanism, electro-magnetic means responsive to a received impulse for operating said shift mechanism from its normal to its shift position, said electro-magnetic means being maintained locked during the receipt of said code combination of impulses, and means responsive to the operation of said printing mechanism for releasing said electro-magnetic means. 70

28. In combination, a printing mechanism, means responsive to received code combinations of impulses for operating said printing mechanism, a shift mechanism, electro-magnetic means for controlling said shift mechanism, said electro-magnetic means being arranged when energized to operate said shift mechanism and to be electrically locked, and means responsive to the operation of said printing mechanism for releasing said electro-magnetic means. 75

29. In combination, a printing mechanism, means responsive to received code combinations of impulses for operating said printing mechanism, a shift mechanism, electro-magnetic means for controlling said shift mechanism, said electro-magnetic means being arranged when energized to operate said shift mechanism and to be locked, means responsive to the operation of said printing mechanism for releasing said electro-magnetic means, and means operative in the event that the succeeding code combinations of impulses is a shift combination for maintaining said electro-magnetic means energized. 80

30. In combination, a printing mechanism, a plurality of electro-magnetic means controlling said printing mechanism, an electro-magnetic shift mechanism for operating said printing mechanism to its shift or its normal position, and a rotating distributor for distributing code combinations of impulses to said electro-magnetic means, and said electro-magnetic shift mechanism. 105

31. In combination, a printing mechanism, a plurality of electro-magnetic means for controlling said printing mechanism, said printing mechanism having a normal and shift position, electro-magnetic means for controlling said printing mechanism to its shift position, and a distributor for distributing received code combinations of impulses to said electro-magnetic printing means and to said shift control electro-magnetic means. 110

32. In combination, a printing mechanism, a plurality of electro-magnetic means for controlling said printing mechanism, said 115

printing mechanism having a normal and shift position, electro-magnetic means for controlling said printing mechanism to its shift position, and a distributor for distributing received code combinations of impulses to said electro-magnetic means and to said shift control electro-magnetic means, said shift control electro-magnetic means being responsive to an impulse received in said code combinations of impulses.

33. In combination, a printing mechanism, a plurality of electro-magnetic means for controlling said printing mechanism, said printing mechanism having a normal and shift position, electro-magnetic means for controlling said printing mechanism to its shift position, and a distributor for distributing received code combinations of impulses to said electro-magnetic printing means and to said shift control electro-magnetic means, said shift control electro-magnetic means being responsive to an impulse received in said code combination of impulses, and means for maintaining said shift electro-magnetic means locked during the reception of said code combination of impulses.

34. In combination, a printing mechanism, a plurality of electro-magnetic means for controlling said printing mechanism, said printing mechanism having a normal and shift position, electro-magnetic means for controlling said printing mechanism to its shift position, a distributor for distributing received code combinations of impulses to said electro-magnetic printing means and to said shift control electro-magnetic means, said shift control electro-magnetic means being responsive to an impulse received in said code combination of impulses, means for maintaining said shift electro-magnetic means locked during the reception of said code combination of impulses, and means responsive to the operation of said printing mechanism for unlocking said shift mechanism.

35. In combination, a printing mechanism, a plurality of electro-magnetic means for controlling said printing mechanism, said printing mechanism having a normal and shift position, electro-magnetic means for controlling said printing mechanism to its shift position, a distributor for distributing received code combinations of impulses to said electro-magnetic printing means, and to said shift control electro-magnetic means, said shift control electro-magnetic means being responsive to an impulse received in said code combination of impulses, means for maintaining said shift electro-magnetic means locked during the reception of said code combination of impulses, means responsive to the operation of said printing mechanism for unlocking said shift mechanism, and means for maintaining said shift electro-magnetic means in its operated position while said received code combinations are being printed.

36. In a register device, a plurality of groups of characters, a permutation mechanism in said register device responsive to code combinations of conditions for selecting a character in each of said groups, and mechanism responsive to a condition accompanying each of said code combinations of conditions for effecting registration of one of said selected characters.

37. A telegraph receiver comprising a selector mechanism embodying a plurality of permutation members responsive to code combinations of marking and spacing conditions; a plurality of groups of characters, a character in each group being selectable by each selective operation of said selector mechanism; shift mechanism and means responsive to a special shift selecting condition accompanying each code combination of conditions for variably controlling said shift mechanism.

38. In a printing telegraph receiver, a plurality of selectable characters, a receiving tape; permutation means responsive to received code combinations of signalling conditions for selecting said characters for printing; and means whereby certain of said selected characters are printed on said tape in offset relation with respect to each other.

39. In a printing telegraph receiver, a plurality of characters arranged in groups; permutation means responsive to received code combinations of signalling conditions for selecting one of said characters for printing; and means whereby the characters of one group are printed in offset relation with respect to characters in another group.

40. In a type bar printer, a tape, a plurality of type bars; means responsive to received code combinations of impulse conditions for selectively operating said type bars to print on said tape; and means whereby certain of the characters printed on said tape are transversely offset with respect to each other.

41. In a type bar printer, a tape; a plurality of type bars each provided with a plurality of characters; means responsive to received code combinations of signalling conditions for selectively operating said type bars to print on said tape; and means responsive to a signalling condition accompanying each code combination of conditions for effecting printing of the different characters of a selected type bar transversely offset with respect to each other on said tape.

42. In a type bar selector; a tape; a plurality of type bars, each having a plurality of characters; means responsive to received code combinations of signalling conditions for selectively operating said type bars to print their characters in either of two positions on said tape transversely offset with respect to each other.

43. In a type bar printer; a plurality of type bars each provided with a "letters" and

- a "figures" character; means responsive to received code combinations of selecting conditions for selectively operating said type bars to print the characters individual thereto; means responsive to an extra signalling condition accompanying each code combination for selecting the "letters" or "figures" character of a selected type bar; and means whereby the "letters" characters are printed 5 in one position and the "figures" characters are printed in a position transversely offset with respect to said "letters" shift characters.
44. In a printing telegraph receiver, a plurality of type bars having "letters" and 10 "figures" case characters; and means whereby the "letters" case characters are printed in one line; and the "figures" case characters are printed in another offset line.
45. In a printing telegraph receiver, a plurality of type bars having lower and upper case characters; a tape; means whereby the lower case characters are printed along one portion of said tape and the upper case characters along another portion; and means responsive to received code combinations of 20 selecting conditions for variably selecting said type bars for printing.
46. In a printing telegraph receiver, a plurality of type bars having "figures" and 30 "letters" characters; a tape; means whereby the "figures" characters are printed along one portion, and the "letters" characters are printed along another portion of said tape; means responsive to received code combinations of signalling conditions for selecting said type bars for printing; and means responsive to an extra signalling condition accompanying each code combination for selecting a "figures" or "letters" character.
47. In a printing telegraph receiver, a plurality of type bars provided with "letters" and "figures" characters; means responsive to received code combinations of signalling conditions selecting said type bars for operation; 40 means responsive to a signalling condition accompanying each code combination for selecting a "letters" or "figures" character of the selected type bar; and means for printing the selected "letters" and "figures" characters 50 in distinctive manner.
48. In a printing recorder; a plurality of characters arranged in groups; permutation means responsive to received code combinations of signalling conditions for selecting a character in each of said groups; and means responsive to a signalling condition accompanying each code combination of conditions to effect the recording of one of the selected characters in a manner indicative of the 55 group from which the character is selected independently of the identity of the character.
49. In a recorder, a plurality of characters arranged in separate groups; permutation 60 means responsive to received code combina-
- tions of conditions for selecting a character in each of said groups; and means for effecting recording of one of said selected characters in a manner indicative of the group containing the character independently of the 70 identity of the character.
50. In a telegraph receiver having a plurality of parts; permutation mechanism responsive to code combinations of signalling conditions for simultaneously selecting a plurality of said parts; and means responsive to a control condition accompanying each code combination to cause operation of only one of the selected parts. 75
51. In a type-bar tape telegraph printer 80 wherein the printing elements are pivotally mounted type-bars provided with a plurality of longitudinally spaced characters, and always rocked to the same printing position; tape feeding means for moving the receiving tape forwardly after each character is printed; and means for causing the different characters on each type bar to be printed on the receiving tape in offset relation with respect to each other. 85
52. In a type-bar printing telegraph machine wherein the printing elements are pivotally mounted typebars provided with a plurality of relatively spaced characters operated to offset printing position with respect to each other; and tape feeding means for moving a receiving tape after each character is printed, engaging the portion of the tape on which characters have been printed, while maintaining an unobstructed view of the 90 printed characters for a substantial interval immediately after the printing thereof. 95
53. A type-bar printing telegraph machine as set forth in claim 52, together with means for maintaining the tape taut without lateral shifting movement thereof at any time as it passes through the machine. 100
54. In a type-bar printing telegraph machine, wherein the printing elements are pivotally mounted type-bars provided with a plurality of spaced type characters always rocked to the same printing position; a platen forming a stop for the type-bar characters; and means for moving a tape across said platen and for maintaining the tape taut in 110 printing position. 115
55. In a type-bar printing telegraph machine, wherein the printing elements are pivotally mounted type-bars which are provided with a plurality of longitudinally spaced type characters always rocked to the same printing position; a platen forming a stop for the type-bar characters; means for moving a tape across said platen; and means for maintaining the tape stationary while shifting said platen laterally of the tape so that 120 only one character will impact against the platen at a time. 125
56. A type-bar printing telegraph machine as set forth in claim 55, together with 130

- an inking ribbon movable across said platen; and means for shifting said ribbon laterally of the tape with said platen.
57. In a selective register, a plurality of 5 groups of characters; means responsive to uniform code combination of signalling conditions for selecting a character in each group; and means responsive to predetermined additional signalling conditions for 10 selectively registering one only of the characters selected by each code combination. 70
58. In a permutation printing telegraph receiver, a platen having a shift and unshift position; printing mechanism having a plurality of characters associated therewith 15 adapted to be variably printed in accordance with the position of said platen; means responsive to code combinations of signalling conditions for simultaneously selecting a 20 character adapted to be printed in each position of said platen and means being also responsive to additional predetermined signalling conditions accompanying each code combination for positioning said platen. 75
59. In combination, a selective recording mechanism having a normal and a shift position, means responsive to uniform code combinations of signalling conditions controlling recording operation in each of said positions; and means responsive to a control condition accompanying each code combination for effecting recording operations either in shift or normal position. 80
60. In a permutation receiver having a 35 normal and a shift position, a plurality of characters recordable in normal position only; a plurality of characters recordable in shift position only, permutation mechanism; means responsive to code combinations of 40 signalling conditions for variably operating said permutation mechanism; means controlled by said permutation mechanism for selecting characters recordable in each position in response to each received code combination; and means responsive to a signalling condition accompanying each code combination for selectively recording a selected character in normal or shift position. 85
61. In a printing telegraph receiver, a 50 printing platen having a shift and a normal position; printing mechanism in operative relation with said platen; means responsive to a uniform combination of impulse conditions for conditioning predetermined characters for printing; and means responsive to a signalling condition accompanying each code combination for controlling the position of said platen. 90
62. In a printing telegraph receiver, a 55 platen having a shift position and normal position; characters arranged to be printed in said shift position, and other characters arranged to be printed in said normal position; means responsive to uniform code combinations of signalling conditions for select- 95
- ing a character for printing in each of said shift positions; and means responsive to predetermined signalling conditions for selectively positioning said platen. 100
63. In a recorder in which characters of a plurality of different groups are to be recorded; permutation means responsive to received code combinations of conditions for conditioning a character in each group for recording, and means responsive to a signal condition accompanying each code combination for controlling the manner in which said characters are recorded to indicate the group thereof but independent of the character itself. 105
64. In a recorder in which characters of a plurality of different classes are to be recorded; permutation mechanism responsive to code combinations of signalling conditions for conditioning a character in each class for recording; and means for recording one of the selected characters in a manner indicative of the class thereof, but independent of the character itself. 110
65. In a printing telegraph receiver, a series of characters to be recorded in offset lines, a permutation device including a plurality of permutation members responsive to code combinations of impulses for selectively operating said characters, both the character 95 to be recorded and the line in which the record is to be made being directly controlled by said permutation device. 115
66. In a printing telegraph receiver, a plurality of groups of characters, permutation means responsive to received code combinations of signalling conditions for selecting a character in each of said groups; a further permutation means responsive to a signalling condition accompanying each code combination of conditions for determining which of said selected characters is to be printed; and means whereby the selected characters of one group are printed in offset relation with respect to the selected characters of another group. 120
67. In a printing receiver, a plurality of groups of characters; permutation means responsive to received code combinations of selecting conditions for selecting a character in each of said groups; permutation means in addition to said first mentioned permutation means responsive to a signalling condition accompanying each code combination for selecting between said groups of characters; a tape and means for printing said selected character on said tape in a manner indicative of the group from which said character has been selected. 125
68. In a printing telegraph receiver; a plurality of groups of characters; a tape; permutation means responsive to received code combinations of signalling conditions for simultaneously selecting a character in each of said groups; permutation means re- 130

sponsive to a signalling condition accompanying each code combination for selecting one of said groups; and means for printing the said selected character of the selected group on said tape and in a manner that indicates the group from which printing occurs independently of the particular character.

5. In testimony whereof I affix my signature.
EDWARD E. KLEINSCHMIDT.
